UNITED STATES PATENT OFFICE.

ANGUS S. MACDONALD, OF GREAT NECK STATION, AND JOHN MULLER, OF FLUSHING, NEW YORK, ASSIGNEES TO THE SNEAD & CO. IRON WORKS, OF JERSEY CITY, NEW JERSEY, A CORPORATION OF NEW JERSEY.

DESIGN FOR A PANEL FOR A LAMP OR A SIMILAR ARTICLE.

53,310.

Specification for Design.

Patented May 13, 1919.

Application filed March 6, 1919. Serial No. 281,097. Term of patent 7 years.

To all whom it may concern:

Be it known that we, ANGUS S. MACDONALD, residing at Great Neck Station, in the county of Nassau and State of New York, and JOHN MULLER, residing at Flushing, in the county of Queens and State of New York, both citizens of the United States, have invented a new, original, and ornamental Design for a Panel for a Lamp or a Similar Article, of which the following is a specification, reference being had to the accompanying drawing, forming a part thereof.

The figure is a side elevation of a panel,

such for example as is used in connection with lamp shades and the like, and it illustrates our novel design of scroll and other ornamental features, associated with pictures illustrating war scenes.

We claim:

The ornamental design for a panel for a lamp or a similar article as shown and described.

In testimony whereof, we have hereunto signed our names.

ANGUS S MACDONALD.
JOHN MULLER.
